UNITED STATES PATENT OFFICE.

FRED A. PHELPS, OF LACONIA, NEW HAMPSHIRE.

DRY VALVE.

942,100.

Specification of Letters Patent.

Patented Dec. 7, 1909.

Application filed April 19, 1906. Serial No. 312,692.

To all whom it may concern:

Be it known that I, FRED A. PHELPS, of Laconia, county of Belknap, and State of New Hampshire, have invented certain new and useful Improvements in Dry Valves, and do hereby declare the following, in connection with the accompanying drawings, to be a full and clear description of my invention.

10 My invention relates to that type of sprinkling systems in which the system pipes are normally free of water, but instead contain air under compression, and in which the supply of water to the system is controlled by a so-called "dry valve" ordinarily located at the base of the riser, the operation of which is automatic upon a certain predetermined variation of air pressure in the system.

20 One object of my invention is a dry valve of few parts, strong and simple in structure, certain and effective in operation, and particularly designed to provide unimpeded passage therethrough for the water.

25 Another object of my invention is an improved dry valve adapted to be tested readily as to its operative condition without necessitating passage of water to the system.

Again an object of my invention is a dry 30 valve in which the control of the water valve is effected by a peculiar and novel system of connections with the air valve, whereby the operation of the air valve at the right pressure is certain, and the release 35 of the water valve complete and substantially instantaneous.

A further object of my invention is a 40 valve, the working parts of which are thoroughly protected from interference or injury through leakage, by a novel system of drainage.

Still another object of my invention is a 45 valve the working parts of which are all inclosed and thoroughly protected within a single body piece, so constructed however as to permit of ready access to such working parts for inspection or resetting.

Other objects of my invention will presently appear.

50 Having set forth the objects and nature of my invention, I will now describe the same in the accompanying drawings in which—

Figure 1, is a view in cross sectional elevation of the valve as assembled and set. 55 Fig. 2, is a similar view showing the parts

in the position they assume during operation of the system. Fig. 3, is a top plan view on the line 3—3 of Fig. 1, the shield 7 being removed. Fig. 4, is a view on the line 4—4 of Fig. 1, looking toward the air valve. Fig. 5, is a bottom plan view of the lever 35. Figs. 6, and 7, are detail views showing means for holding the main or water valve elevated.

Referring to the drawings, the body 1 of the valve is shown as provided with a flanged opening 2 for connection with the water supply pipe and with a flanged opening 3 for connection with the system riser. It is also provided with a drain outlet 4 for draining the system through the opening 3 and for taking off the water from the supply pipe when the valve is being tested, as hereinafter to be described. A hand hole 5 and cover 6 therefor in the body of the valve permits of access thereto in resetting the check valve after operation, and a shield 7 hinged as at 8 or otherwise movable permits of access to the air valve and its connections. In the riser 9 above the valve is shown a normally open gate valve 10 for cutting off communication with the system during testing or at other times, and in the water supply pipe 11 below the valve is shown a second normally open gate valve 12 for cutting off the water supply during resetting or when desired. A third gate valve 13 is provided in the drain pipe 14 and is normally closed, being open during testing or to drain the system.

The interior of the body 1 of the dry valve is comprised of three compartments 15, 16 and 17. The compartment 15 is normally in open communication with the system and it is with this chamber that the drain 4 communicates when the valve 13 is open. Between the chambers 15 and 16 is the check valve 18 hinged at 19 and normally maintained closed as shown in Fig. 1 by the air pressure in the system, but adapted when actuated by the water pressure to assume the position shown in Fig. 2. It will be noted that the body 1 is of such form and the check valve 18 so mounted that in the position shown in Fig. 2 the valve 18 lies entirely out of the path of the water of the system. Between the chambers 15 and 17 is the air or controller valve 20 hinged at 21 and normally held closed as shown in Fig. 1 by the system air pressure. As shown in Fig. 2 the valve 20 is likewise closed and out of the

path of the water during operation of the system. The water supply inlet to the chamber 16 is normally closed as shown in Fig. 1 by the main or water valve 22. This 5 valve, however, upon operation of the system assumes the position shown in Fig. 2 entirely out of the path of the passing water. There is a passage 23 between the chambers 16 and 17, and this passage is normally 10 open as shown in Fig. 1. The passage is controlled, however, by a valve 24, in the present instance shown as a double valve with the valve 22 and mounted on a single valve rod or strut 25 with the water valve. 15 It will be seen upon reference to Fig. 2 that upon the automatic operation of the dry valve the passage 23 between the chambers 16 and 17 is closed by the valve 24. The chamber 16 is provided with a normally 20 open drain 26, controlled, however, by a check valve 27. As shown in Fig. 2 the valve 27 is closed during operation of the system. The chamber 17 is likewise provided with a normally open drain 28, the 25 drains 26 and 28 in the present instance communicating with a common off-take 29. It will be seen that the drain 28 by reason of the passage 23 might serve the chamber 16 as well as the chamber 17. 30 Coming now to the operative connections between the air or controller valve and the main or water valve it will be noted that the strut or water valve stem 25 is loosely attached at 30 as to the water valve and passes 35 up through the opening 23, terminating in the chamber 17 in a rounded or spherical end 31. Secured within the chamber 17 as by screws 32 is a bracket bearing 33 and loosely engaging this bearing by means of 40 knife edged bearings 34 is a lever 35 shown in detail in Fig. 5. Adjustably mounted on the lever 35 is a screw 36 the lower end 37 of which projects through the lever and is concaved to register with and form a bearing 45 for the spherical end 31 of the water valve strut 25. The lever 35 has therein an opening 38, through which as shown in Fig. 2 the strut 25 is adapted to protrude during operation of the system. Also mounted 50 within the chamber 17 as by screws 39 is a bracket bearing 40. Loosely engaging the bracket 40 by knife bearings 41 is a bell crank lever 42. One arm 43 of said lever engages as by means of a toggle or link 44 the 55 air valve 20. The other arm 45 of the bell crank lever engages through toggles 46 and 47 the outer end of the lever 35. The arm 45 is loosely linked to the toggle 46 and the latter linked in the same manner to the toggle 60 47. The toggle 47 is not linked to the lever 35 but merely engages the same as by a knife bearing 48. The toggle 44 is loosely linked to the arm 43, but engages with the valve 20 in the same manner that the toggle 48 engages 65 the lever 35. The toggle 46 engages

at 49 the upper end 50 of a toggle post 51 secured as by bolts 52 to the wall of the chamber 17. The normal position of the bell crank lever and toggles is that shown in Fig. 1, but as shown in Fig. 2 the operation 70 of the air valve has caused the end 49 of the toggle 46 to pass the end 50 of the toggle post 51 with the result that the whole connection has collapsed. Within the chamber 17 and attached to the face of the air valve 75 20 as by means of bolts 53 is a catch 54 adapted upon contact with the inner face of the valve seat or with any suitable projection to limit the outward movement or play 80 of the valve 20.

To hold the lever 35 in the position shown in Fig. 2 a catch of any suitable design may be applied to the inside of the shield 7 or otherwise mounted in the chamber 17. Arrangement can also be made for holding the air valve 20 closed when the shield 7 is open as in setting. Such an arrangement might be a fastening device attached to the catch 54 and to the shield 7, or a pawl arranged to engage the catch 54 when the shield is 90 opened and to be disengaged therefrom when the shield is closed.

Operation: The valve having been set the normal position of its parts is that indicated in Fig. 1 from which it will be seen that the main valve 22, the check valve 18 and the air valve 20 are all closed, the passage 23 open, the check valve 27 in the chamber 16 drain open, the gate valves 10 and 12 in the riser and water supply open and the gate valve 13 95 in the drain 14 closed. The hand hole 5 is securely closed and the shield 7 likewise closed. In this position leakage through the valve 22 from the water pipe into the chamber 16 is taken care of by the drain 26, but if this is closed by failure of the check valve 27 to properly open the leakage drainage from the chamber 16 will be through the passage 23 into the chamber 17 and thence to drain 28. The chamber 15 is under the same pressure of the system but for the better priming and sealing of the valves 18 and 20 is normally filled with water to the level indicated.

The valves 18, 20 and 24 are all here 100 shown as of the same area or size, although this similarity is obviously unnecessary. The system of communicating links and levers between the valves 20 and 22 is such 105 that the air pressure normally in the system and acting against the outer face of the valve 20 is sufficient to maintain the valve 22 closed against the water pressure in the supply mains. The leverage through the lever 35 is such that a pressure of 1 lb. on the air valve normally resists a pressure of 9 lbs. on the water valve. Assuming the pressure in the water mains to be 90 lbs. per square inch and the area of the water valve 22 to be 28.27 sq. in. the hydrostatic pres- 110 115 120 125 130

sure exerted on the water valve and through the strut 25 to the lever would be 2544.3 lbs. This would be reduced by the 9 to 1 lever 35 and transferred through the toggles 47, 46, bell crank lever 42, toggle 44 to air valve 20 to a pressure of 282.7 lbs. This would be the pressure tending to open the valve 20 were there no air pressure in the system. Assuming, however, an air pressure of 30 lbs. per sq. in. in the system there would be exerted against the outer face of the valve 20 a pressure of 848.1 lbs. holding that valve to its seat against the pressure of 282.7 lbs. on the other side. Reducing the air pressure in the system to 10 lbs. the pressures on either side of the valve 20 balance and upon any further reduction of the system pressure the valve 20 opens. The amount of the opening of the valve 20 is restricted by the catch 54. The opening has been sufficient, however, to cause the end 49 of the toggle 46 to slip over the end 50 of the toggle post 51. This causes the toggle connections to collapse as shown in Fig. 2 and the lever 35 being thus freed swings to the position shown in Fig. 2 under the influence of the pressure on the strut from the water valve. This movement of the lever 35 frees the end 31 of the strut from its seat 37 in the screw 36, and thus freed, the strut 25 passes freely up through the opening 36 in the lever to the position shown in Fig. 2. On upward movement of the strut 25 the water valve 22 is thrown wide open and the upper face of said valve carrying as it does the valve 24 seats the latter to close the opening 23 between the chambers 16 and 17. The water from the supply pipe then rushing into the chamber 16 throws open the check valve 18, simultaneously closes the check valve 27 in the chamber 15 and passes upward through chamber 15 to the riser. Upon collapse of the toggle connections the pressure remaining in the system will ordinarily be sufficient to at once reclose the valve 20. If, however, for any reason such as the simultaneous opening of many sprinklers there not remain in the system sufficient air pressure to reseat the valve 20 this valve will be immediately reseated by the water rushing through chamber 15 from the water supply.

The valve is reset as follows: The gate valve 12 in the water supply pipe is first closed and the valve 13 in the drain pipe 14 opened until all the water in the system has been drained through chamber 15 into drain 14. The valve 13 is then closed. Hand hole cover 6 is then removed and the check valve 18 lifted to its normal position. The shield 7 is then removed, the air valve 20 inspected and seated. The chamber 15 is then filled through a tunnel with water to the height indicated in Fig. 1 and after the valve in said tunnel is closed air is pumped into the system to a pressure of from 30 to

40 lbs. The water valve 22 is then seated and the levers and toggles reset. The adjusting screw 36 is turned down lightly by hand and the gate valve 12 in the supply pipe partly opened. By a suitable wrench the screw 36 is then turned down until the water valve 22 is tight. Thereupon the gate valve 12 in the supply system may be opened wide and strapped or locked and the shield 7 closed and locked.

To test the operation of the valve without passing water to the system the gate valve 10 in the riser is closed and the valve 13 in the drain 14 opened. Upon operation of the device, as above described in connection with feed to the system, the water from the supply mains instead of passing to the system would pass instead through the drain pipe 14.

Although I have described in detail a structure embodying my invention it is obvious that numerous changes may be made in such structure without involving a departure from the true scope of the invention and the principles involved therein.

It may occur when the water valve is open, as in Fig. 2, that the reduction in pressure may be such as to permit the water valve to fall by gravity, thus interfering with the desired uninterrupted flow of the water. In such case automatic means may be used for holding the water-valve elevated. Two devices for this purpose are shown in Figs. 6 and 7. As shown in Fig. 6, two holding dogs 55, are loosely pivoted on knife bearings 56 on opposite sides of the water-valve stem 25, and the upper end of the stem is reduced with an intermediate beveled shoulder 57. When the water-valve is closed, the dogs 55, do not touch the stem. When the valve is lifted, the shoulder 57, throws the dogs up, and they then bite on the enlarged portion of stem 25, and hold it lifted. In Fig. 7, spring-pressed pivoted pawls 58, cooperate with ratchet-grooves 59, on stem 25, for the same purpose. When the shield 7, is opened, the dogs 55, or pawls 58, are released by hand from the stem 25, and the water-valve closes by gravity. These parts are made of bronze or other non-corrosive metal.

I claim—

1. In a sprinkling system, a dry valve comprising, a chamber to communicate with the system, a second chamber to communicate with the water supply, a passage between said first and second chambers and a check valve in said passage, a main valve between said second chamber and the supply, said first chamber having an opening therefrom and an air valve in said opening mounted to open inwardly into said first chamber, said air valve being closed both normally and during operation of the system, connections between said main and air

- valves by means of which, with one pressure in the system, said air valve maintains said main valve closed, and through which connections, upon a predetermined variation of that pressure, the air valve is momentarily actuated by the main valve to release the latter entirely.
2. In a sprinkling system, a dry valve comprising, a chamber to communicate with the system and with the water supply, said chamber having an opening therefrom, an air valve in said opening mounted to open inwardly into said chamber, said air valve being closed both normally and during operation of the system, connections outside of said chamber between said main valve and the external face of said air valve by means of which, with one pressure in the system, said air valve maintains said main valve closed, and through which connections, upon a predetermined variation of that pressure, the air valve is momentarily actuated by the main valve to entirely release the latter.
3. In a sprinkling system, a dry valve comprising, a chamber to communicate with the system, a second chamber to communicate with the water supply, a passage between said first and second chambers and a check valve in said passage, a main valve between said second chamber and the supply, said first chamber having an opening therefrom and an air valve in said opening mounted to open inwardly into said first chamber, said air valve being normally closed by the air pressure in the system, connections between said main and air valves by means of which said air valve maintains said main valve closed, and through which connections, upon a predetermined variation of that pressure, the air valve is momentarily actuated, said connections being constructed to break upon such actuation of the air valve to permit the main valve to open under the water pressure and the air valve to again close under the system air pressure.
4. In a sprinkling system, a dry valve comprising, a chamber to communicate with the system, a second chamber to communicate with the water supply, a passage between said first and second chambers and a check valve in said passage, a main valve between said second chamber and the supply, said first chamber having an opening therefrom and an air valve in said opening mounted to open inwardly into said first chamber, means in connection with said air valve to actuate the same upon a predetermined relative variation of system and supply pressure, means normally maintaining said main valve tight but actuated upon movement of the air valve to release said main valve entirely, said air valve being thereupon freed to be reseated by the system air pressure.
5. In a sprinkling system, a dry valve comprising, a chamber in communication with the system and with the supply, a main valve between the supply and said chamber, an air valve in communication with the system and maintained normally closed by the pressure in the system, connections between said main and air valves comprising a strut on the main valve, a pivoted lever, an intermediate point of which is normally engaged by said strut, a bell crank lever, a toggle post, linked toggles, one of which normally engages said toggle post and one arm of said bell crank lever, and another of which engages the free end of said first named lever, and a joint between the other arm of said bell crank lever and the air valve, whereby movement of the main valve is communicated to the air valve.
6. In a sprinkling system, a dry valve comprising, a chamber in communication with the system and with the supply, a main valve between the supply and said chamber, an air valve in communication with the system and maintained normally closed by the pressure in the system, connections between said main and air valves comprising a strut on the main valve, a pivoted lever, an intermediate point of which is normally engaged by said strut, a bell crank lever, a toggle post, linked toggles, one of which normally engages said toggle post and one arm of said bell crank lever, and another of which engages the free end of said first named lever, and a joint between the other arm of said bell crank lever and the air valve, the engagement of the strut and first named lever being such that upon movement of the air valve through the aforesaid connections, the strut is freed from the other connections and permits the main valve to open freely.
7. In a sprinkling system, a dry valve comprising, a chamber in communication with the system and with the supply, a main valve between the supply and said chamber, an air valve in communication with the system and maintained normally closed by the pressure in the system, connections between said main and air valves comprising a strut on the main valve, a pivoted lever, an intermediate point of which is normally engaged by said strut, a bell crank lever, a toggle post, linked toggles, one of which normally engages said toggle post and one arm of said bell crank lever, and another of which engages the free end of said first named lever and a joint between the other arm of said bell crank lever and the air valve, the engagement of said toggle post and toggle being broken upon movement of the air valve, whereby the connections collapse.
8. In a sprinkling system, a dry valve, comprising a chamber in communication with the system and with the supply, a main valve between the supply and said chamber, an air valve in communication with the sys-

tem and maintained normally closed by the pressure in the system, connections between said main and air valves comprising a strut on the main valve, a pivoted lever, an intermediate point of which is normally engaged by said strut, a bell crank lever, a toggle post, linked toggles, one of which normally engages said toggle post and one arm of said bell crank lever, and another of which 10 engages the free end of said first named lever, and a joint between the other arm of said bell crank lever and the air valve, whereby the toggles collapse, and the engagement of said strut and lever being such 15 that upon collapse of the toggles the strut is freed from the lever and permits the main valve to open freely.

9. In a sprinkling system, a dry valve comprising, a chamber to communicate with the system, a second chamber to communicate on the one hand with the supply and on the other hand with the first chamber, a third chamber always vented to the open air to communicate abnormally with the first 25 chamber and normally with the second chamber, a normally closed check valve between the first and second chambers, a normally closed main valve between the supply and the second chamber, a normally closed 30 air valve between the first and third chambers and connections between said main and air valves through said second and third chambers.

10. In a sprinkling system, a dry valve comprising, a chamber to communicate with the system, a second chamber to communicate on the one hand with the supply and on the other hand with the first chamber, a third chamber to communicate on the one 40 hand with the first chamber and on the other hand with the second chamber, a normally closed check valve between the first and second chambers, a normally closed main valve between the supply and the second chamber, a normally closed air valve between the first and third chambers, connections 45 between said main and air valves through said second and third chambers, and a normally open drain from said second chamber, a normally open fourth valve between the second and third chambers, a normally closed air valve between the first and third chambers and connections 50 between said main and air valves through said second and third chambers.

11. In a sprinkling system, a dry valve comprising, a chamber to communicate with the system, a second chamber to communicate on the one hand with the supply and on the other hand with the first chamber, a third chamber to communicate on the one hand with the first chamber and on the other hand with the second chamber, a normally closed check valve between the first 55 and second chambers, a normally closed main valve between the supply and the second chamber, a normally open fourth valve between the second and third chambers, a normally closed air valve between the first and third chambers and connections 60 between said main and air valves through said second and third chambers, a normally closed check valve between the first and second chambers, a normally closed main valve between the supply and the second chamber, a normally closed air valve between the first and third chambers, connections 65 between said main and air valves through said second and third chambers, a drain from said third chamber and a normally open drain from said second chamber.

tween said main and air valves through said second and third chambers, the main, the air and the fourth valves being so connected that upon actuation of the air valve the main valve opens and the aforesaid fourth valve closes, and the check valve being free to open under water pressure after the opening of the main valve.

12. In a sprinkling system, a dry valve comprising, a chamber to communicate with the system, a second chamber to communicate on the one hand with the supply and on the other hand with the first chamber, a third chamber to communicate abnormally with the first chamber and normally with the second chamber, a normally closed check valve between the first and second chambers, a normally closed main valve between the supply and the second chamber, a normally closed air valve between the first and third chambers, connections between said main and air valves through said second and third chambers, open drains from said second and third chambers, and a normally open check valve adapted to close the drain from the 90 second chamber when the main valve is open.

13. In a sprinkling system, a dry valve comprising, a chamber to communicate with the system, a second chamber to communicate on the one hand with the supply and on the other hand with the first chamber, a third chamber to communicate on the one hand with the first chamber and on the other hand with the second chamber, a normally closed check valve between the first and second chambers, a normally closed main valve between the supply and the second chamber, a normally closed air valve between the first and third chambers, connections 100 between said main and air valves through said second and third chambers, and a normally open drain from said second chamber.

14. In a sprinkling system, a dry valve comprising, a chamber to communicate with the system, a second chamber to communicate on the one hand with the supply and on the other hand with the first chamber, a third chamber to communicate on the one hand with the first chamber and on the other hand with the second chamber, a normally closed check valve between the first and second chambers, a normally closed main valve between the supply and the second chamber, a normally closed air valve between the first and third chambers, connections 110 between said main and air valves through said second and third chambers, and a normally open drain from said second chamber.

15. In a sprinkling system, a dry valve comprising, a chamber to communicate with the system, a second chamber to communicate on the one hand with the supply and 120

on the other hand with the first chamber, a third chamber to communicate on the one hand with the first chamber and on the other hand with the second chamber, a normally closed check valve between the first and second chambers, a normally closed main valve between the supply and the second chamber, a normally closed air valve between the first and third chambers, connections between 10 said main and air valves through said second and third chambers, said third chamber having a movable cover to permit of access to said connections.

16. In a sprinkling system, a dry valve comprising, a chamber to communicate with the system, a second chamber to communicate on the one hand with the supply and on the other hand with the first chamber, a third chamber to communicate on the one hand with the first chamber and on the other hand with the second chamber, a normally closed check valve between the first and second chambers, a normally closed main valve between the supply and the second chambers, 20 a normally closed air valve between the first and third chambers, a system of multiplying levers between said main and air valves

whereby the different pressures on each may be balanced.

17. In a sprinkling system, a dry valve comprising, a chamber to communicate with the system and with the water supply, said chamber having an opening therefrom, an air valve closing said opening and mounted to open inwardly into said chamber, said air valve being closed both normally and during operation of the system, connections outside of said chamber between said main valves and the external face of said air valve, by means of which, with one pressure in the system, said air valve maintains said main valve closed, and through which connections, upon a variation of that pressure, the air valve is actuated by the main valve, and said main valve is wholly released.

In witness whereof, I have hereunto signed my name in the presence of two subscribing witnesses.
